UNITED STATES PATENT OFFICE

2,562,307

PIVOTED JAW TYPE, INTERNALLY
THREADED SOCKET WRENCH

Walter W. Flugrath, New Braunfels, Tex.

Application February 24, 1947, Serial No. 730,349

2 Claims. (Cl. 81—53)

1

This invention relates to a novel construction of wrench especially adapted for use in plumbing and pipe fitting for screwing short nipples into pipes or which may be also utilized for setting stud bolts.

More particularly, it is an object of the invention to provide a wrench especially intended to be utilized in threadedly applying short nipples which are externally threaded throughout their length and the threads of which are ordinarily damaged by attempting to apply such nipples with a conventional pipe wrench.

Another object of the invention is to provide a wrench which may be utilized for applying pipes of any length by engagement with a threaded end thereof in such a manner as to prevent marring of the pipe as frequently occurs with the use of conventional pipe wrenches having toothed or serrated faces.

Still another object of the invention is to provide a wrench having a threaded socket for receiving the threaded end of a nipple or pipe for effectively holding said end for rotation of the pipe or nipple by the wrench.

Still another object of the invention is to provide a wrench having a head provided with a threaded socket and which is formed of pivotally connected sections capable of being opened for receiving a threaded end of a pipe or nipple and thereafter latched in a closed position for retaining said pipe or nipple end within the wrench head socket.

Various other objects and advantages of the invention will hereinafter become more fully apparent from the following description of the drawing, illustrating a preferred embodiment thereof, and wherein:

Figure 1 is a top plan view of a preferred embodiment of the wrench;

Figure 2 is a fragmentary edge elevational view of one end thereof;

Figure 3 is a fragmentary bottom plan view of said end;

Figure 4 is a view similar to Figure 3 but showing the movable jaw of the wrench in an open position;

Figure 5 is a cross sectional view taken substantially along a plane as indicated by the line 5—5 of Figure 1;

Figure 6 is a longitudinal sectional view thereof taken substantially along a plane as indicated by the line 6—6 of Figure 1, and

Figure 7 is a fragmentary perspective and exploded view of portions of the wrench head.

Referring more specifically to the drawing, the improved wrench in its entirety is designated

2

generally 8 and comprises an elongated handle 9 having a wrench head 10 at one end thereof and a wrench head 10a at its opposite end.

The wrench head 10 is substantially circular and is formed of substantially semi-circular sections 11 and 12. The section 11 is formed integral with the handle 9 and the section 12 is hingedly connected to the section 11 at 13, at one end of the meeting faces of the jaws or sections 11 and 12 forming the head 10.

The hinge, designated generally 13, as best illustrated in Figures 5 and 7 includes barrel portions 14 and 15 which form integral parts of the jaws 11 and 12, respectively, and which are laterally offset, as best seen in Figure 7. Said jaws 11 and 12 are also provided in alignment with their barrel portions 14 and 15 with arcuate recesses 16 and 17, respectively, for receiving the barrel portions 15 and 14, respectively, for arranging 20 said barrel portions in alignment for receiving a hinge pin 18, also constituting a part of the hinge 13.

The fixed jaw 11 is provided with a recess 19 at the side edge thereof remote from the hinge 13 and which is provided with a stepped portion forming a downwardly facing shoulder 20. The hinged jaw 12 is provided at its free end with a depending barrel portion 21 which extends from one side to intermediate of the sides thereof and which is disposed to be received in a portion of the recess 19 when the jaw 12 is in a closed position, as seen in Figures 1 and 3. A latch member 22 is provided with an offset barrel portion 23 at its upper end which is disposed in alignment with the barrel 21 for receiving a hinge pin 24 for pivotally connecting the latch element 22 to the free end of the hinged jaw 12. The latch 22 tapers in thickness toward its free end and is provided on its inner side and adjacent its pivoted end with a stepped portion forming an 35 upwardly facing shoulder 25 arranged to engage under the shoulder 20 when the head 10 is closed, as seen in Figures 1 and 3 and when the latch element 22 is disposed in the recess 19.

The head 10 is provided on its under side with 45 an internally threaded socket 26 which extends from said under side to adjacent the opposite, upper side thereof, as best seen in Figure 6. The recess 26 is formed half by the fixed jaw 11 and half by the hinged jaw 12, each of which parts is 50 provided with a semicircular recess opening outwardly of its under side and abutting edge.

The wrench 8 is especially adapted for use in threadedly applying short, externally threaded nipples in pipe fittings or plumbing. Such nipples are ordinarily threaded at least at both ends

thereof and are generally so short that when one end is being screwed into a fitting it is necessary to engage the opposite, externally threaded end with a pipe wrench. This usually results in deforming the threads engaged by the pipe wrench so that they cannot be properly threaded into another fitting.

With the present invention, the latch 22 is swung outwardly so that the jaw 12 will be released to be swung to an open position as seen in Figure 4 and the end of the nipple, as indicated at 21 in Figure 6 in dotted lines, may then be inserted into the opened socket 26 and disposed in abutting engagement with the closed end thereof. The hinge jaw 12 is then swung to a closed position and secured by the latch 22. The nipple 21 can then be turned by the wrench 8 without danger of damaging the threads thereof located in the socket 26 due to the fact that the turning movement of the wrench 8 in a direction for applying the nipple 21 will merely cause the end of the nipple, engaged by the socket 26, to abut more firmly against the closed end of the socket. After the nipple has been applied, the latch 22 is disengaged and the jaw 12 swung to an open position for detaching the wrench 8 therefrom.

The wrench head 10a, located at the opposite end of the handle 9 is identical in construction to the wrench head 10 and differs therefrom only in that it is of a different size or at least is provided with a different size nipple receiving socket.

Obviously, the wrench 8 may be utilized for applying stud bolts or for applying long pipe, both ends of which are externally threaded, where it is desired to avoid marring the surface of the pipe with a conventional pipe wrench.

Various modifications and changes in the construction of the invention as heretofore disclosed are contemplated and may obviously be resorted to, without departing from the spirit or scope of the invention as hereinafter defined by the appended claims.

I claim as my invention:

1. In a wrench for applying externally threaded nipples or the like, a substantially flat relatively thin wrench head comprising a fixed jaw and a movable jaw pivotally connected to the fixed jaw, an elongated handle formed integral with and extending from the fixed jaw, said fixed jaw being disposed transversely of the longitudinal axis of the handle, said head

being provided with an internally threaded socket opening outwardly of one side only thereof and having substantially equal portions formed by each of the two jaws, said jaws having abutting faces disposed transversely to the longitudinal axis of the handle, and said socket being adapted to engage one of the externally threaded ends of a nipple for rotating the nipple, when the wrench is turned.

- 10 2. In a wrench for applying externally threaded nipples or the like, a substantially flat relatively thin wrench head comprising a fixed jaw and a movable jaw pivotally connected to the fixed jaw, said head being provided with
15 an internally threaded socket opening outwardly of one side only thereof and having substantially equal portions formed by each of the two jaws, said socket being adapted to engage one of the externally threaded ends of a nipple for
20 rotating the nipple when the wrench is turned, said jaws having laterally offset barrel portions at corresponding ends of their jaw faces, each of said jaws being recessed at said ends for receiving the barrel portion of the other jaw, a
25 hinge pin extending through said barrel portions and combining therewith to form the pivot of the jaws, and latch means carried by the
30 jaws in closed position.

WALTER W. FLUGRATH.
